UNITED STATES PATENT OFFICE.

ROBERT MORRIS, OF WINTHROP, MAINE.

SHADE-FIXTURE.

No. 796,238.

Specification of Letters Patent.

Patented Aug. 1, 1905.

Application filed February 15, 1905. Serial No. 245,756.

To all whom it may concern:

Be it known that I, ROBERT MORRIS, a citizen of the United States of America, residing at Winthrop, in the county of Kennebec and State of Maine, have invented certain new and useful Improvements in Shade-Fixtures, of which the following is a specification.

This invention relates to curtain and shade hangers; and it has reference particularly to a combined adjustable bracket for the shade and curtain.

The object of this invention is to produce a bracket which may be applied to the top of the window-casing without marring the exposed surface of such casing.

Furthermore, the object is to provide means for adjusting the bracket for the shade vertically or transversely with relation to the window.

Furthermore, the object of the invention is to produce a combination-bracket in which the curtain-pole bracket may be readily detached without disturbing the hanger or the bracket of the shade-roller.

Furthermore, the object of the invention is to produce a bracket which will possess advantages in points of simplicity and inexpensive construction and durability and prove satisfactory and efficient in use.

With the foregoing and other objects in view the invention consists in the details of construction and in the arrangement and combination of parts to be hereinafter more fully set forth and specifically claimed.

In describing the invention in detail reference will be had to the accompanying drawings, forming part of this specification, wherein like characters denote like and corresponding parts in the several views, in which—

Figure 1 is a view in elevation of a portion of a window with the invention applied. Fig. 2 is a vertical sectional view of the hanger and brackets. Fig. 3 is a perspective view of the hanger. Fig. 4 is a perspective view of one of the shade-brackets. Fig. 5 is a perspective view of one of the pole-brackets. Fig. 6 is a perspective view of the washer.

In the drawings, 1 indicates a vertically-disposed member of a hanger, and 2 a top plate at right angles thereto. The top plate has spurs or notches 3, which are embedded

in the upper edge of the window-casing for the purpose of retaining the hanger in place, the top plate supporting the other portion.

The vertical member 1 has a centrally-positioned longitudinally-extending slot in which a set-screw 4 is slidable. The portion 1 has recessed front and rear surfaces, and the head of the said screw is slidable in the recess in the rear face. A combined washer and bracket-holder 6 is slidable in the recess in the other surface of the member 1, and the screw passes therethrough, and the thumb-nut on the screw serves to bind the washer in any position of adjustment. A shade-bracket 7 has a slot 8, through which the screw is passed, and said screw is slidable transversely on the part 1 in order to adjust the brackets with relation to each other to accommodate shade-rollers of varying lengths.

The washer has its end curved to form sockets 9, and the curtain-pole bracket 10 is slidable therein and made adjustable with relation to the shade-roller bracket. The curtain-pole bracket is formed of wire bent to produce the arm 11, and the two ends 12 are slidable in the sockets of the washer.

It will be observed from the foregoing that the brackets may be moved up and down or transversely of the portion 1 and secured in place against accidental movement after the adjustment.

The construction, operation, and advantages will, it is thought, be fully understood from the foregoing description, it being noted that various changes may be resorted to in the proportions and details of construction for successfully carrying the invention into practice without departing from the scope thereof.

Having fully described my invention, what I claim as new, and desire to secure by Letters Patent, is—

1. In a shade and curtain fixture, a hanger, a combined washer and bracket-holder on the hanger, the ends of said combined washer and bracket-holder being bent to form sockets, a bracket secured in the sockets, a bracket slidable between the bent ends and means for binding the parts together.

2. In a device of the character described, a hanger comprising a plate having spurs and a

vertically-disposed member formed integral with the plate, a combined washer and bracket-holder on the vertically-disposed member, said combined washer and bracket-holder having its ends bent to form sockets, a bracket supported by the sockets and means for binding the parts together.

In testimony whereof I affix my signature, in the presence of two witnesses, this 2d day of February, 1905.

ROBERT MORRIS.
